Frederick H. Larter,

By Drake & Co. Atty's.

UNITED STATES PATENT OFFICE.

FREDERICK H. LARTER, OF NEWARK, NEW JERSEY.

BUTTON.

SPECIFICATION forming part of Letters Patent No. 479,191, dated July 19, 1892.

Application filed November 7, 1891. Serial No. 411,154. (No model.)

To all whom it may concern:

Be it known that I, FREDERICK H. LARTER, a citizen of the United States, residing at Newark, in the county of Essex and State of New Jersey, have invented certain new and useful Improvements in Sleeve-Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to facilitate the operation of applying the button to the cuff and to save accidental separation, and thus obtain greater security for the cuff.

The invention consists in the improved cuff-button and in the arrangements and combinations of parts, substantially as will be hereinafter set forth, and finally embodied in the clauses of the claim.

Referring to the accompanying drawings, 25 in which like letters indicate corresponding parts in each of the several figures, Figures 1 and 2 are plans of the button, showing the heads in different positions; and Figs. 3, 4, and 5 are detail views of the link, Fig. 4 being an enlarged section on line *x* and Fig. 5 a section on line *y*.

In said drawings, *a a'* are the heads, having eyes or shanks *a²*, and *b* indicates the link of the button. Said link is permanently 35 secured to one of said heads and removable or separable from the other. The link is of peculiar construction and consists of a wire bent at its opposite ends to form a link with an open side. An eye *b'* may be formed either

40 in bending the wire at one of said ends or by soldering a separate piece *b²* within or on the concave side of the bend, as shown in Fig. 2. At one of the extremities of the bent wire is soldered or fixed a tubular wire *d*, 45 which lies substantially parallel with the part of the wire between the bent extremities, and at the opposite extremity of said bent wire is soldered a short section *e* of hollow wire, which forms a recess or small cham-

ber to receive the projecting extremity of 50 the pin or tongue *f*. Said pin or tongue is arranged in the fixed tubular part *d* and is adapted to close the opening remaining between said part and the part *e*, the said pin or tongue being adapted to slide longitudinally in said tubular wire *d* to open or close the opening. It is held normally closed by a spring *h*, arranged within the tube *d*, which spring bears against the end of the pin and forces the same outward, so that it lies at its 60 opposite end within the tube *e*. The pin *f* is provided with a nail-piece *g*, which slides in a slot in the tube, as will be understood upon reference to Figs. 3 and 4. By simply pressing the nail-piece backward against the 65 spring the link is opened to admit the insertion or removal of the separable head. By means of the spring-controlled sliding tongue the link cannot be accidentally opened and the separable head removed therefrom as 70 readily as heretofore; but, on the other hand, the said separable head is held with greater certainty and security, and when a separation is desired the same can be effected with increased convenience.

I am aware that heretofore in cuff-buttons an open button-shank has been employed in connection with a solid link, or one having no opening, such as I have shown herein. In my device I avoid the objections to such 80 construction and employ a solid shank, such as will pass through the buttonhole without catching and will be capable of withstanding the pressure used in such operation without being bent out of operative condition, as 85 will be understood.

Having thus described the invention, what I claim as new is—

1. The combination of heads *a a'*, a link 90 permanently secured to one of said heads and separable from the other, the said link having an opening and being provided with a tube formed adjacent to said opening, and a sliding tongue to open or close said opening, substantially as set forth.

2. The combination of heads *a a'*, a link 95 permanently secured to one of said heads and separable from the other, said link con-

sisting of a wire bent at its opposite ends and provided with tubular extremities, and a sliding tongue and spring inserted in one of said extremities, the tongue being adapted to normally close the opening between said extremities, substantially as set forth.

In testimony that I claim the foregoing I

have hereunto set my hand this 4th day of November, 1891.

FREDERICK H. LARTER.
